DESIGN FOR A COMBINED VENTILATOR CASING AND SUPPORT THEREFOR

Gerald L. Schwarz, Cleveland, Ohio, assignor to
Air Controls, Inc., Cleveland, Ohio, a corpora-
tion of Ohio

Application July 24, 1936, Serial No. 64,024

Term of patent 7 years

To all whom it may concern:

Be it known that I, Gerald L. Schwarz, a citizen of the United States, residing at 11802 Thornwood Avenue, Cleveland, in the county of Cuyahoga and State of Ohio, have invented a new, original, and ornamental Design for a Combined Ventilator Casing and Support Therefor, of which the following is a specification, reference being had to the accompanying drawing, forming part thereof.

Fig. 1 is a front perspective view of a combined ventilator casing and support therefor showing my new design.

Fig. 2 is a rear elevational view of the same.

Fig. 3 is a side elevational view looking from the right of Fig. 1.

The support for the ventilator casing is shown in dotted lines in the drawing. The dominant features of my design reside in the portions shown in full lines.

I claim:

The ornamental design for a combined ventila-
tor casing and support therefor, as shown and
described.

GERALD L. SCHWARZ.
